UNITED STATES PATENT OFFICE.

BENJAMIN W. WOOSTER, OF ALBANY, NEW YORK.

IMPROVEMENT IN HANDLES FOR COFFINS.

Specification forming part of Letters Patent No. 34,387, dated February 11, 1862.

To all whom it may concern:

Be it known that I, BENJAMIN W. WOOSTER, of the city of Albany, State of New York, have invented a new and useful Method of Constructing Coffin-Handles with their Ornamental Plates; and I declare the following specification, with the drawings accompanying it and forming part thereof, to be a full and perfect description of my invention.

In the drawings similar letters denote the same parts of the apparatus.

For the purpose of carrying coffins conveniently it is customary to attach metallic handles to them—two or more to each side. These are of the form and construction commonly used for chests and drawers—that is, a loop of metal A, (see Fig. 1,) whose ends are pivoted through upright standards B B, projecting from a stout metal plate C, the whole being secured to the wood by screws D, passing through the plate.

My improvement consists in attaching the handles to the wood by a strong loop independently of the plate, the plate being subsequently fixed to the wood.

Figure 2 shows the handle, and Fig. 3 the loop and plate separated from each other in plan; Fig. 4, the parts all together in plan; Figs. 5 and 6, the same in section through the vertical line x y, Fig. 4.

H is the handle, which has at e (see Fig. 2) a journal fitted to a strong loop or socket E. This loop has stout lugs a and b, projecting above and below it, through which by strong screws it is secured to the sides W of the coffin. This being done, the plate P is put into its place. The plate has a flat rim r and a raised or convex body P, and also has a niche f f f f cut into its upper edge to pass the lug b of the loop under its raised body,

and the under part of the loop E and the lug a are cut away to allow the edges of the niche f f f f to pass under them until the edge of the plate and the outer edge of a coincide. The width of the rim r and of lug a are made equal to give a symmetrical appearance to the whole, as shown in Fig. 4. When the plate is in its place, it is fastened with light screws or pins to the wood, and the work is complete. The back part of journal e has a projecting toe n, Figs. 5 and 6, so fitted that when the handle H is raised from its hanging position, as shown in Fig. 6, to its horizontal one, Fig. 5, it shall stop against the side of the loop and prevent the handle from turning any farther upward. This mode of construction not only makes the handle independent of the plate, but allows the fastenings to be close to the body E of the loop, and consequently more reliable than when at the edge of the plate. It also allows the adaptation to one form of handle of various shaped and differently ornamented plates, which is an economic feature of consequence in the manufacture and sale of these handles.

My invention, although intended primarily for coffins, I design to use for bureaus, chests, and other appliances where the loop-handle is used.

What I claim as my invention, and desire to secure by Letters Patent, is—

The combination of the handle H and its loop E, constructed as described, with the ornamental plate P, for the purposes set forth in the within specification.

B. W. WOOSTER.
